EDWARD F. GUIDINGER, OF BARTLESVILLE, OKLAHOMA, ASSIGNOR TO PHILLIPS
PETROLEUM COMPANY, OF BARTLESVILLE, OKLAHOMA, A CORPORATION OF DELA-
WARE

CASING HEAD

Application filed January 6, 1930. Serial No. 418,853.

This invention relates to improvements in well equipment, and more especially to improvements in oil wells of the type employing a casing and tubing.

5 To facilitate an understanding of the present invention, it may be well at the beginning, to explain the use of the two different terms "casing" and "tubing". An oil well is nearly always completed for production with 10 a string of steel pipe extending from the surface of the ground to the top of the oil sand, or near it. This pipe is called the well casing. When the well is to use a gas lift, another string of smaller pipe, called tubing, 15 is inserted through the casing, the lower end of this tubing being placed wherever the well functions the best from the standpoint of oil production and quantity of gas required.

In some wells, the gas is admitted through 20 the tubing and passes out at the bottom through the oil, rising to the top of the well and through the space between the tubing and the casing. In other set-ups, the procedure is reversed, the gas being injected into the 25 well in the space between the casing and tubing, mixing at the bottom with the oil, and the mixture rising to the top through the tubing. The latter method of hook-up is the one nearly always used in fields where the 30 quality of the oil is such that there is a tendency toward deposition of paraffin on the walls of the flow column. In a set-up of this character, it is not only necessary that there be a tight seal between the tubing and the 35 casing at the well mouth, but the sealing means should be simple, effective, and should lend itself to a quick and easy change in amount of tubing in the well.

The primary object of the present invention 40 is to provide such a sealing means of a novel type, and one which will be relatively inexpensive to manufacture.

Another object is to furnish such a sealing means, preferably comprising only two parts, 45 one a packing head, and the other, a tubing hanger.

A still further object is to provide a combined casing head and tubing hanger, which will contact by means of ground surfaces, and 50 which will eliminate the use of packing, bolts,

screws, etc., at the casing head of the well. Another object is to furnish a casing head having a ground surface to contact with the corresponding surface of a tubing hanger, and also provided with means for protecting 55 said ground surface to prevent mutilation of the same while the tubing is being fed into the casing.

With the foregoing objects outlined and with other objects in view which will appear as the description proceeds, the invention consists in the novel features hereinafter described in detail, illustrated in the accompanying drawings, and more particularly 60 pointed out in the appended claims.

Referring to the drawings,

Fig. 1 is a diametrical vertical sectional view of the upper end of a well casing, my improved casing head and tubing hanger, 65 and a portion of the well tubing.

Fig. 2 is a plan view of the casing head partly in horizontal section, the section being taken on the line 2-2 of Fig. 3.

Fig. 3 is an elevation of the head, partly 70 in vertical section, the section being taken on line 3-3 of Fig. 3.

Fig. 4 is a plan view of my novel tubing hanger.

Fig. 5 is an elevation of the same, partly 75 in vertical section, the section being taken on the line 5-5 of Fig. 4.

By reference to the drawings, it may be seen that an ordinary well casing 6 is provided with internal threads that are engaged by external threads on my casing head 8. 80 This head is preferably formed of a single piece of metal, such as steel, and it is of tubular form, the lower portion being provided with the threads 7 on its exterior, and a downwardly flared or frusto-conical surface 85 9 on its interior. While the surface 9 may be of any suitable inclination, I prefer to taper the same about six and one-quarter inches per foot, as I have found that such a surface effectively guides the tubing, (hereinafter referred to), as the latter is raised in, or withdrawn from the casing.

The upper end of the surface 9 merges into a cylindrical surface 10, which extends upwardly on the inside of the head to an up- 90 95 100

wardly flaring or frusto-conical surface 11 that acts as a guide for the tubing when the latter is descending, and preferably has a taper of about ten inches per foot. This surface 11 acts as a protector for a frusto-conical ground sealing surface 12, which is arranged above the surface 11, and preferably has a slightly different inclination from the latter surface. For example, the flared surface 12, 10 may have a taper of about fourteen inches per foot.

It is highly essential that the surface 12 be protected from scarring or mutilation, and this is insured, not alone by the guide surface 11, but by an annular groove or channel 13, 15 which is arranged within the head, and is located between the surfaces 11 and 12. As a further precaution, an annular recess or rabbet 14 is located in the head between the upper end of the surface 12 and the horizontal top surface 15 of the head, to prevent any elevating means placed on the surface 15 from contacting with or scarring the upper end of the surface 12.

25 The head terminates at its upper end in an annular flange 16, so as to provide an enlargement on which the tubing elevator may rest, and below this flange, the head has the usual lateral screw threaded openings 17, to be attached to pipes that lead to or from the head.

30 This novel head cooperates with the tubing hanger 18, which is shown in detail in Figs. 4 and 5, and this hanger is also preferably made of a single piece of steel, and is provided with a centrally disposed vertical bore, having internal screw threads 19 and 20, in order that the hanger may be interposed between two sections 21 and 22 of the tubing string and function as a joint in such string. 35 40 To allow the hanger to be readily operated by a wrench, the threads 19 are formed in an upwardly extending boss or nipple 23, having angularly arranged surfaces 24 on its exterior.

45 The lower portion of the hanger is provided with an external frusto-conical ground surface 25, which is tapered to conform with the surface 12, and as the surfaces 12 and 25 are ground and snugly interfit when the hanger 18 is resting on the head 8, it will be understood that the weight of the tubing string will thus provide a sealed joint which will prevent the exit of gas.

In operation, the weight of the tubing, 50 when resting on the tapered surface 12, gives a perfectly tight seal, preventing loss of gas, but when it is decided to take the tubing out of the well, or run in additional joints, it is only necessary to lift the string of tubing 55 with the ordinary elevator and tubing blocks, whereupon the tapered tubing coupling 18 rises from the tapered seat 12, on the head, and can be lifted up high enough to take the hanger 18 out of the string of tubing. 60 65 After this is done, additional joints of tub-

ing may be run through the head, the couplings of such tubing passing freely through the bore of the head.

As the tubing is moved into the well, the 70 couplings have a tendency to strike the tapered surface 12, which would, in time, prevent the proper seating of the head 18, and result in a leaky joint. To prevent this, the head has been provided with the tapered 75 guide surface 11 for the purpose of guiding the tubing to facilitate the passing of the couplings thereof through the head. The recess 14, during such operation, prevents any 80 possibility of mutilation of the surface 12 by the tubing elevators, which rest on the top of the head during the process of running tubing in, or out of the well. By taking the two precautions of shaping the lower surface 11 as a guide for the tubing couplings, and the recess 14 at the upper end of the surface 85 12 to prevent mutilation, the latter surface, which is the sealing ring, is practically assured of being kept free from any damage.

So far as I am aware, there is no head made 90 that will serve this purpose, in as simple a way, and with as few parts as the head which I have devised. The ordinary head used, consists generally of a casing head, a tubing support, and numerous glands, packing rings, slips, bolts, etc. Most of such heads must be 95 taken off the casing in order to get additional joints of tubing in or out of the hole. My improved head permits the free movement of the tubing with a minimum number of parts to be handled, and is very effective in its purpose.

Some efforts have been made to provide 100 heads capable of producing the same results as mine, but my head differs from them in at least three different details. In the first place, the prior art heads have at their lower ends, internal, instead of external threads. An external thread, such as shown at 7 in my drawings, is much cheaper to cut in the shop, and from that standpoint, more desirable.

110 In the second place, each of the prior proposals, while suggesting the use of a tapered surface, shows only one tapered surface in the head for the reception of the tubing collar, and also has packing of some sort. In one instance, it is proposed to wrap the tapered tubing collar with a layer of lead or 115 similar sheet packing, and rely on the seal of this packing to hold the pressure. In another case, it is suggested to cut grooves in the tapered tubing collar or hanger in which are to be placed "square hydraulic packing", thus relying on the contact of this packing 120 with the tapered seat in the head for cutting off the pressure. In my head, I rely solely on the fit secured by proper machining of both the tapered seat and the tapered collar for the pressure shut-off. In practice, I have demonstrated that if these tapered surfaces are properly machined, and then ground to 125

a fit, no difficulty is had in making a tight joint if the surfaces are perfectly clean when the tubing string is set down.

A third particular way in which the prior proposals differ from mine, is that in the prior structures, no provision is made for protection of the tapered seat in the head, against abrasion from collars on the tubing string, while being run through the head. It is obvious, as the tubing string is run into the casing, joint after joint being screwed into the top collar, and the entire string being lowered into the hole through the head, that the coupling collars will have a tendency to strike on one side of the circular opening of the head. If these collars strike the surface 12, some mutilation is to be expected, thereby preventing a perfect contact between the surfaces 12 and 25. In my head, I take care of this by providing the guide surface 11 on which the collars, as they pass into the hole, may strike and be deflected towards the center of the hole, making it impossible for the collar to hang on any part of the head as it passes through, and whatever mutilation may occur by this striking, is on this guide surface 11. When the hanger 18 is set down, in order to effect the shut-off, the tapered surface 25 on the tubing collar does not rest in contact with any part of the surface 11, but contacts only with the surface 12, which has been arranged purposely for this contact. As stated heretofore, the top edge of the surface 12 is turned off for about half an inch below the flat top 15 of the head, and when elevators which support the tubing strings by contact under a tubing collar, rest on the flat top of the head 8, it is practically impossible for any mutilation to occur on the upper tapered surface 12. It will therefore be seen that the surface 11 and the groove 14 insure the protection of the surface 12, so that the latter may always properly cooperate with the surface 25 to make a perfect seal without the use of packing, bolts or the like.

Another advantage of my head over any of those on the market, resides in the extreme simplicity of construction and assembly, due to the fact that it consists of only two parts. Any head which involves the use of such parts, together with packing, bolts, auxiliary flanges, etc., adds to the expense and difficulty of equipping a well, oftentimes delaying work or making the job more or less incomplete. These heads are usually installed on wells which have a tendency to flow naturally under rock pressure, while the work is being done, and the necessity of installing packing, placing bolts, and tightening these at a well, having a tendency to flow while the work is being done, makes it a real advantage to use my improved head which does not require any unusual effort to finish the job.

From the foregoing it is believed that the

construction, operation and advantages of my invention may be readily understood, and I am aware that changes may be made in the details disclosed, without departing from the spirit of the invention, as expressed in the claims.

What I claim and desire to secure by Letters Patent is:

1. A casing head comprising a metal tubular member having in the upper portion of its bore, an upwardly flaring ground contact surface, the bore being provided with an annular recess spacing the upper end of said surface from the top of the head, an upwardly flared guide surface arranged below said contact surface, the bore having an annular groove arranged between the contact surface and the guide surface.

2. In combination, a casing head comprising a metal tubular member having in the upper portion of its bore, an upwardly flaring ground contact surface, the bore being provided with an annular recess spacing the upper end of said surface from the top of the head, an upwardly flared guide surface arranged below said contact surface, the bore having an annular groove arranged between the contact surface and the guide surface, and a tubing hanger provided with an external ground surface conforming to and contacting with the ground surface of the head.

In testimony whereof, I affix my signature.

EDWARD F. GUIDINGER.
